UNITED STATES PATENT OFFICE.

JAMES BECKNER, OF ST. JOSEPH, MISSOURI.

TRACTION-ENGINE.

SPECIFICATION forming part of Letters Patent No. 452,592, dated May 19, 1891.

Application filed November 7, 1890. Serial No. 370,598. (No model.)

To all whom it may concern:

Be it known that I, JAMES BECKNER, a citizen of the United States, residing at St. Joseph, in the county of Buchanan and State of Missouri, have invented certain new and useful Improvements in Traction Steam-Engines; and I do declare the following to be a full, clear, and exact description of the invention, such as will enable others skilled in the art to 5 to which it appertains to make and use the same.

My invention relates to improvements in portable steam-engines; and it has for its object to secure increased power at a reduced consumption of fuel as compared with other 15 engines of a similar nature and to provide for the successful accomplishment of the various outdoor work which is required of an engine of this character.

With these and other ends in view my invention consists in the combinations of devices and novel construction and arrangement of parts, as will be hereinafter fully described and claimed.

To enable others to readily understand my 25 invention, I will now proceed to a detailed description thereof in connection with the accompanying drawings, in which—

Figure 1 is a plan view of a portable engine embodying my improvements. Fig. 2 is 30 a vertical longitudinal section thereof on the line $x-x$ of Fig. 1. Figs. 3, 4, and 5 are detail perspective views of parts of my improvements. Fig. 6 is a plan view of the grate, and Fig. 7 is a sectional view of the turn-table.

Like letters and numerals of reference denote 35 corresponding parts in all the figures of the drawings, referring to which—

A designates the carrying-frame of my improved portable engine.

B C are the front and rear axles, respectively.

D are the rear supporting and driving 45 wheels, and E are the smaller wheels on the front axle, which is made to do the duty of steering the machine by the steering appliance, presently to be referred to.

The carrying-frame consists of two parts 1 50 2, one of which is arranged within the other, each part or member having side bars arranged parallel with the corresponding bars of the other part, and the inner member 2 of the frame has its rear ends secured directly

to the rear cross-bar of the outer part 1, while the forward ends of said inner part or member converge on inclined lines, as at 2', (see 55 dotted lines in Fig. 1,) and are united in any suitable manner to each other and to the front cross-bar of the outer part 1 of the frame.

Situated between the side bars of the inner 60 part of the carrying-frame is the upright boiler F, and this boiler is suspended from the carrying-frame and rigidly attached thereto by means of hangers 3 4, one of which is illustrated in detail in Fig. 5 of the drawings. The hanger is right-angled in form, and the vertical arm is bolted or otherwise rigidly secured to the boiler-shell, while the horizontal arm has long depending bolts 5, which straddle one of the side bars of the inner 65 member of the carrying-frame, which bolts receive straps or plates 6, that bear against the lower sides of the side bar of the frame.

Between the side bars of the two parts 1 2 70 of the carrying-frame and on opposite sides of the upright boiler are placed the two cylinders G H, each of which is firmly secured in place on the carrying-frame in any suitable manner. In these cylinders operate the pistons g h, (indicated by dotted lines in Figs. 80 1 and 2,) and the piston-rods g' h' extend rearward from the cylinders and connect, respectively, with the cranks i j on the driving-shaft I. Said driving-shaft extends transversely across the frame 1 in rear of the 85 boiler and the rear axle C, and it is journaled in suitable fixed bearings J J' on the side bars of the inner and outer parts of the carrying-frame. The cranks i j of said driving-shaft are set diametrically opposite to each 90 other, and as two cylinders and two pistons are employed I am enabled to overcome the common objection of dead-centers in the operation of the engines of ordinary form, as by this arrangement employed dead-centers 95 are wholly avoided, the connection between the cranks and piston-rods being accomplished in any practical manner with which others skilled in this art are familiar.

Steam is supplied to the steam-chests of the 100 two cylinders by means of a supply-pipe 8, which enters the steam-space of the vertical boiler, preferably at the front thereof, and it leads downward from the top to a point about

half-way down the boiler, at which point the pipe 8 is divided into two branch pipes 9 9', which extend horizontally around the sides of the boiler and enter the steam-chests 10 11 5 of the two cylinders G II. The valve (not shown) of each cylinder has its rod 12 extending rearward from its steam-chest, and it is connected to a head 13, which in turn connects with two rods 14 14', the rear ends of 10 which are provided with yokes that fit around eccentricities 15 on the driving-shaft I for the proper operation of the controlling-valve, it being understood that each cylinder has this valve mechanism just described.

15 To adapt the improved traction-engine for use for a number of hours without renewing the fuel and water supply and without the attendance of a tank-wagon and at the same time promote economy in the use of fuel, I provide the traction-engine with its own water-chamber, fuel-reservoir, means for purifying the water before its admission to the tank, and means for utilizing a portion of the exhaust-steam to heat the feed-water to a considerable temperature before admitting it to the boiler.

The water-tank 16 is situated at the front end of the carrying-frame and extends, preferably, from one side of the frame to the other, to which frame said tank is rigidly secured in any preferable way, and on the top of this tank is erected the magazine 17, which consists in one embodiment of my invention of a box-shaped magazine formed by vertical 35 walls or flanges on the top of the water-tank.

At the rear end of the carrying-frame 1 is arranged the primary water-receiving vessel 18, which is suitably fixed to the frame at or about the plane of the bars of said frame, and 40 in this primary receiving-vessel is situated a suitable filtering or water-purifying apparatus for the purpose of cleansing the feed-water of sediment and impurities before passing the feed-water to the tank. The connection between the primary vessel 18 and the feed-water tank 16 is secured by means of a pipe 19, extending underneath the boiler, and the feed-water is passed from the tank 16 to the boiler by means of a pipe 20, a suitable injector being connected to the feed-water pipe 45 to force the water into the boiler, as will be readily understood.

The feed-water in the tank 16 is heated by a portion of the exhaust-steam from each cylinder, which exhaust-steam is conveyed from said cylinder to the tank by means of pipes 21, which extend from the cylinders to the tank and discharge the steam into the same, while the remaining portion of the exhaust-55 steam is conducted by pipes 22 to the smoke-stack of the boiler and is discharged into the same to promote the draft of the boiler.

By the employment of the filtering and heating devices for the feed-water and the means 60 for promoting draft in the smoke-stack I am enabled to utilize the exhaust-steam and to effect a material saving in the use of fuel, as

the purifying of the water and heating thereof secures an economy of about thirty (30) per cent. of fuel, at least approximately. Furthermore, by reducing the force and volume of exhaust-steam discharged into the smoke-stack I am enabled to overcome the objection of creating too much draft therein and forcing out sparks and live cinders, and I further provide a spark-arrester 26 over the outlet of the smoke-stack, which embodies a fine screen of gauze in its construction to more effectually obviate the escape of small live sparks. 80

A throttle-valve 27 is provided in the steam-supply pipe 8, and a suitable lever 28 extends therefrom within convenient reach of the attendant's seat 29, erected on a suitable standard at the rear of the feed-water-heating tank. Another lever 30 is also situated within reach of the attendant for the purpose of reversing the engines, and this lever is linked to the rock-shaft 31, journaled in suitable bearings transversely across the front of the boiler, said shaft having arms 32, which are connected by links 33 with the reverse mechanism of the engines, as will be readily understood by those skilled in the art to which this invention relates. 95

The appliances by which the traction-engine is steered are located within reach from the seat, and I employ a vertical shaft 35, which is suitably journaled in the feed-water tank, the upper end of which shaft has an ordinary hand-wheel 36, while to the lower end of the shaft is secured a horizontal pinion 35', and carried by another vertical shaft 35'', journaled in the feed-water tank adjacent to the shaft 35, is a large horizontal gear 36'', with which the pinion 35' meshes. Carried by the shaft 35'' above the gear 36'' is a sprocket-wheel 37. Around this sprocket-wheel passes a chain 38, and the ends of this chain are connected by swivels 29 to the front axle near the ends thereof, so that as the shaft is turned in one direction or the other the front axle will be correspondingly turned to steer the machine in the desired direction. 105

The driving-shaft I at the rear of the boiler is provided at its ends with small gear-pinions K, which mesh with corresponding pinions on short counter-shafts L, L, that are arranged in rear of the driving-shaft driven thereby, and are journaled in suitable bearings on the sides of the inner and outer parts of the carrying-frame. These counter-shafts are furthermore provided at their ends with spur gear-wheels m, which lie in the vertical planes of the wheels D, whereby the counter-shafts are independently geared to the rear carrying-wheels to rotate the same, and as said shafts are driven at uniform speed from the common driving-shaft they operate to rotate the wheels D uniformly and propel the machine forward. 115

The rear axle C of the machine is securely connected to the carrying-frame by means of the clips 39, one of which is illustrated in Fig. 4, each clip consisting of the top plate having

the depending arm and the connecting-plates to straps, which are fitted in said arms and clamped against the bottom edge of the axle by nuts, as shown.

5 To adapt the machine for the various purposes to which one of this class is employed, in addition to its use of hauling loads, thrashers, &c., I provide a windlass or drum 40 in rear of the main driving-shaft I and adapted 10 to be operated thereby. This drum has its shaft 41 journaled in suitable blocks or standards 42, which are adapted to be adjustably secured by bolts to the inner member 2 of the frame, which member is provided at suitable intervals with vertical bolt-holes to receive the securing-bolts of said standards, whereby said standards and the drum carried thereby may be adjusted or fixed at various distances from the driving-shaft, 15 20 and on said drum-shaft is rigidly secured two spur-gears 43 44, one of which is larger than the other. When the standards of the drum 40 are secured on member 2 of the frame some distance away from the driving-shaft I, 25 its larger gear 43 is adapted to mesh with a suitable gear 45, fastened to the driving-shaft I by a key or cotter to secure a slow motion to said drum; but when a faster motion is desired the drum and its supports are moved 30 close to the driving-shaft and the gear 45 adjusted lengthwise of the shaft I to mesh with the smaller gear 44, as is obvious. Around the spool of this drum is coiled the 35 rope 46 for lifting weights and other purposes, which rope is adapted to pass rearward and from the machine between suitable guide-blocks 47, journaled on the rear cross-bar of the carrying-frame. The spool is adapted to be inclosed by a removable cover to convert 40 the same from a windlass into a leather-faced drum for various purposes, and in Fig. 3 of the drawings I have illustrated a suitable covering, which consists of a series of slats 50, having the side edges inclined or beveled, 45 as shown, and attached to pliable strips 51, which extend lengthwise of the cover, and are adapted to fasten said cover around the drum, with the ends of the slats resting on the heads of the drum, the whole surface of the cover 50 being concealed by a layer of leather or other friction-surface material 52, which is suitably secured to the slats. The cover can be readily applied to the windlass, and it affords a solid firm support for the rope; but it can 55 also be easily removed and the simple spool used, as may be required.

The vertical boiler is, as usual, provided with an ash-pit 53 and with a grate 54; but I prefer to employ a grate of that form known 60 as a "shaking-grate," in which I use certain stationary portions 55 and the sectional hinged rocking portions 55', operated from a common rock-shaft 56, which shaft has a depending arm 57, to which is connected a 65 rod or link 58, that extends through the ash-pit door and is provided with a handle to enable the attendant to operate the grate while

occupying the seat at the front of the machine. I also employ a turn-table 60 for the support of the front end of the carrying-frame 70 on the front axle, and which is constructed to permit the front axle to accommodate itself to the irregularities and unevenness in the ground over which the machine is moving. Attached to the top of the front axle is a lower 75 section 61, having an annular channel therein to receive ball-bearings, which enter a corresponding channel in the intermediate section 62, and said lower section has a central socket-piece 63, which enters a corresponding socket 80 in the lower side of the intermediate section, said socket and socket-piece being concentric with the annular ball-bearing channels and fitting snugly together to insure the necessary horizontal movements of the axle 85 B. The opposing faces of the intermediate and upper sections 62 and 65 are concaved, and in the center of one section is a socket which receives the stud or lug 66 on the other section, a horizontal pivot bolt or shaft 67 90 passing through the intermediate and top sections to permit the desired play or movement of the axle in accommodating itself to the irregularities in the ground.

In the practical construction of my improvements the front and rear wheels are each to be built of metal with metallic fellies, hubs, and spokes, with the parts suitably united or socketed together.

The operation and advantages of my invention will be readily understood from the foregoing description, taken in connection with the drawings, and I do not therefore deem it necessary to repeat the same here.

Changes in many instances in the form and proportion of parts and details of construction can be made without departing from the spirit of my invention.

Having described my invention, what I claim, and desire to secure by Letters Patent, 110 is—

1. In a traction-engine, substantially as described, the combination of the frame supporting the boiler, the steam-cylinders, the double-crank shaft operated by the pistons 115 of the cylinders, the laterally-adjustable gear carried by said crank-shaft, the drum-shaft, and the fast and slow gears carried by said drum-shaft and adapted to engage the gear of the double-crank shaft, substantially as 120 specified.

2. In a traction-engine, the combination of the driving-shaft, the drum-shaft adjustable toward and from the driving-shaft and carrying the slow and fast speed-gears, and the 125 driving-gear adjustable on the driving-shaft to gear with either speed-gear on the drum-shaft, substantially as specified.

3. In a traction-engine, the combination, with the front axle, of the pivot-section attached to the upper side thereof and having an annular channel to receive ball-bearings and a central socket-piece, an intermediate section having a socket in its under side to

receive the central piece of the lower section, the vertical pivot bolt or shaft 67, taking through and connecting the intermediate and lower sections, and the top section connected to the intermediate section and lower sections and to the feed-motor tank, substantially as specified.

4. In a traction-engine, the carrying-frame, the rear axle, and the connection therefor, comprising the top plate provided with the integral arms depending from the four cor-

ners which straddle the axle and frame, and the plates fitted on said arms and clamped against the axle by nuts, substantially as specified.

In testimony whereof I affix my signature in presence of two witnesses. 15

JAMES BECKNER.
